COIN CONTROL MECHANISM FOR ELECTRIC CIRCUITS

Albert W. Shertenlieb, Long Beach, N. Y.

Application July 14, 1938, Serial No. 219,231

3 Claims. (Cl. 194—6)

This invention relates generally to a coin control mechanism for electric circuits, but more specifically to a coin control mechanism in association with an electric clock whereby an electric circuit can be maintained closed for a predetermined period by and after the introduction of a coin or metallic token.

The main object of the invention resides in the provision of a coin control mechanism in association with an electric time clock whereby an electrical circuit can be closed and opened after running for a predetermined period.

Another object of the invention is to provide a coin control means as applied to an electric clock whereby the clock may be started after the introduction of a coin or metallic token and stopped at a predetermined interval of time.

A still further object of the invention resides in the provision of an electric clock which will run for a predetermined period only after the insertion of a coin thereby serving as an incentive to saving money.

These objects and other incidental ends and advantages of the invention will hereinafter appear in the progress of the disclosure and as pointed out in the appended claims.

Accompanying this specification are drawings showing a preferred form of the invention wherein corresponding reference characters designate corresponding parts throughout the several views and wherein:

Figure 1 is a top plan view of an electric clock having a coin control mechanism and an auxiliary chamber associated therewith.

Figure 2 is a front view in elevation of Figure 1.

Figure 3 is a side view in section of the device showing the auxiliary chamber and the coin control mechanism contained therein.

Figure 4 is a fragmentary front view in elevation partly in section of the circuit closing means of the coin control mechanism within the coin control chamber.

Figure 5 is a fragmentary view in side elevation showing the relationship between the circuit closing disks, the dial plate, the hour hand and toothed wheel.

Figure 6 is a diagrammatical view showing the electrical circuit between the coin control mechanism and the motor of the clock.

In accordance with the invention and in accordance with a preferred form shown, numeral 10 indicates an electric clock casing containing a clock mechanism and motor chamber 10', the clock mechanism and motor not being shown, 11

represents a conventional marginal dial while 12 represents a glass window enclosing the minute hand 13, the hour hand 14 and the second hand 15 against the front dial wall 12' of the clock casing. Front dial wall 12' at one side is provided with an opening 16 for partial penetration of a toothed wheel as will hereinafter be described.

Secured to one side of clock casing 10 is an auxiliary housing or chamber 17 having an intermediate protruding front round portion 17a, 10 an opposite and partly rounded rear portion 17b and top offset portions 17c and 17d between which is a coin chute 18a.

On the inner side of the front dial wall 12' of the casing 10 is secured an upright support 18 15 which is adapted to act as a bearing for a shaft 19 running horizontally within the casing 10 and contiguous to the inner side of the dial wall 12' and having at the outer extremity a wheel 20 having teeth 20a, 20b, 20c and 20d thereon, the 20 said teeth being preferably spaced at 90 degrees and being adapted to penetrate opening 16 on wall 12' of the casing.

Two spaced non-conducting uprights 21 are secured at the lower ends of the inner face of front 25 wall of housing 17 by means of screws or rivets 22' penetrating holes 22 in the said uprights. Secured to the front faces of uprights 21 are two metallic strips 23 having rearwardly offset portions 23a at the top thereof bearing down upon 30 upwardly projecting conducting saddle members 24' mounted in slits 21a at the top of the uprights, the strips 23 being secured to uprights 21 by means of screws 24. Saddle members 24' are adapted to be in electrical and frictional engagement with metallic sleeves 25 fixed on shaft 19, the said sleeves being spaced by means of a non-conductive bushing 26. Shaft 19 with sleeves 25 thereon penetrates standards 23, non-conductive bushing 26 and two disks 27 each being on one 40 side of the bushing. Disks 27 are conductors secured to sleeves 25 and have a series of inwardly disposed, aligned and radial slits preferably ninety degrees apart as indicated by letters A, B, C and D, said disks having outer lateral bearing 45 lugs 27a disposed against the inner opposing walls of uprights 21. If desirable, a non-conductive strip 28 may be secured to the inner side of wall 17a to insulate said wall from the circumferential 50 surfaces of disks 27.

Numerical 29 indicates a coin box disposed within the lower part of chamber 17, the means of withdrawing coin box 29 from the said chamber not being shown as such means are merely con- 55

ventional. 30 indicates a set of leads coming from a source of electric power and each lead is connected to metallic strip 23 by means of screws 24. 31 indicates diagrammatically a clock 5 motor while 32 is a coin or metallic token which is adapted to close the electric circuit of the motor by means of descending through coin chute 18a and falling into one of the aligned slits A, B, C or D in disks 27. Numerals 33, 34 and 35 indicate circuit leads or conductors whereby the circuit shown in Figure 6 is opened and closed by dropping a coin 32 into chute 18a to conductively connect the disks 27.

Figure 6 shows how the leads 33 and 35 emanating from a source of electric current close the circuit of motor 31 whenever the coin 32 is permitted to go into chute 18a. Thus, when coin 32 falls into one of the aligned slits such as B of disks 27 shown in Figure 5, lead 33 becomes electrically connected to lead 34 by means of strips 23, conducting saddle members 24', disks 27 and metallic sleeves 25, the coin 32 electrically joining disks 27 together.

According to the disposition of slits A, B, C and D and teeth 20a, 20b, 20c and 20d, as shown in Figure 5, it is seen how the insertion of a coin into chute 18a will fall directly into one slit of disks 27 such as B. When this is done, the electric clock circuit is closed and will remain closed 30 until the coin in slit B is in the opposite diametrical position at which time the coin falls out and breaks the circuit. In order that slit B attain the opposite diametrical position, the discs 27 must be rotated by means of disc 20. This is 35 accomplished by the consecutive engagement of the teeth 20b, 20a, 20c and 20d with the hour hand 14. As shown in Figure 5, the hour hand 14 is ready to engage the tooth 20b and within a twelve hour sweep of the hour hand 14, the tooth 40 20b will move 90 degrees. Within the next twelve hour sweep of hour hand 14, tooth 20a will be engaged, rotating tooth 20b another 90 degrees, thereby bringing slit B to its opposite diametrical position for the falling out of the coin to break 45 the circuit. It is possible to feed chute 18a with a series of coins so that if a housewife should leave her home for an extended period of time, the clock will remain going and at the same time she will have saved in her "clock bank" a sum 50 of money.

I wish it understood that minor changes and variations in the construction, position, material and integration of parts of the embodiment of the invention and in the predetermined time intervals set forth hereinabove, may all be resorted to without departing from the spirit of the invention and without departing from the scope of the appended claims.

I claim:

1. In a coin controlled circuit closer, a motor driven time clock forming part of the said circuit, a rotatable coin carrier having spaced and insulated conducting members electrically connected to terminals forming a break in the given circuit, a plurality of diametrically opposite sets of aligned slots in said conducting members, the circuit being closed by an inserted coin engaging the conducting members in a set of said slots, means mechanically operated by the clock to rotate the coin carrier whereby at predetermined intervals the coin falls out of a set of aligned slots thereby breaking the circuit. 10 15 20

2. In a coin controlled circuit closer, a motor driven time clock forming part of the said circuit, a rotatable coin carrier having coin receiving slits therein, the said carrier being connected to opposite terminals and normally forming a break in the given circuit, the circuit being closed by an inserted coin electrically engaging one of the 25 said slits to close the said circuit, means mechanically operated by the clock mechanism to rotate the coin carrier whereby at predetermined intervals the coin falls out of one of the slits in the said carrier, thereby breaking the circuit. 30 35 40 45

3. In a coin controlled circuit closer, a motor driven time clock forming part of the said circuit, a coin carrier having two conducting members electrically connected to terminals forming a break in the given circuit, a plurality of diametrically opposite sets of aligned slots in said 40 conducting members, the circuit being closed by an inserted coin engaging the conducting members in a set of said slots, means mechanically operated by a part of the clock mechanism to displace the coin carrier whereby at predetermined intervals the coin falls out of a set of aligned slots thereby breaking the circuit. 45

ALBERT W. SHERTELIEB.
